UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A HANDLE FOR COMBS, BRUSHES, &c.

SPECIFICATION forming part of Design No. 19,704, dated March 18, 1890.

Application filed February 24, 1890. Serial No. 341,627. Term of patent 7 years.

To all whom it may concern:

Be it known that I, HENRY BERRY, a citizen of the United States, residing at Shelton, in the State of Connecticut, have invented and produced a new and original Design for a Handle for Combs, Brushes, Mirrors, and other Articles, of which the following is a specification, reference being had to the accompanying drawing, forming a part thereof, and which shows a plan view of a comb having a handle embodying the design made the subject hereof.

The leading features of my design consist in the form or outline of the handle and the ornamental scrolls thereon, as shown in the drawing, and more particularly referred to hereinafter.

The lower portion of the handle, lettered A, is convex along its front edge B and concave along its back or rear edge C, and said handle about its said convex edge and its lower end is embordered by the foliate scroll D, the leaves

of which trend inward and substantially inclose, except at one edge, the fluted scroll E, covering the main body of the flower portion 25 of the handle. The upper portion of the handle is concave at F along its front edge and convex at G along its back or rear edge, and said edges are embordered by the foliate scrolls H I, surmounted at their upper ends 30 by an ornamental scroll-cap J and inclosing the spray of leaves and flowers L.

What I claim as my invention, and desire to secure by Letters Patent, is—

The design for a handle for combs and other 35 articles, substantially as shown and described.

In witness whereof I hereunto affix my signature, at Shelton, Connecticut, this 18th day of February, 1890.

HENRY BERRY.

In presence of—

WESLEY L. CLARK,
JNO. J. HADLOW.
